(57) **CLAIM**

The ornamental design for a dialysis recharger cabinet, as shown and described.

DESCRIPTION

FIG. 1 is a perspective view of a dialysis recharger cabinet; FIG. 2 is a front view thereof; FIG. 3 is a rear view thereof; FIG. 4 is a left side view thereof; FIG. 5 is a right side view thereof; and, FIG. 6 is a front view of a dialysis recharger cabinet according to a second embodiment.

The broken lines shown in the figures represent portions of the dialysis recharger cabinet that form no part of the claimed design.
